UNITED STATES PATENT OFFICE.

ARTHUR BOID MASON, OF ASHLAND, OHIO.

RAILROAD-TIE.

No. 827,808.

Specification of Letters Patent.

Patented Aug. 7, 1906.

Application filed May 10, 1906. Serial No. 316,185.

To all whom it may concern:

Be it known that I, ARTHUR BOID MASON, a citizen of the United States, residing at Ashland, in the county of Ashland and State 5 of Ohio, have invented a new and useful Railroad-Tie, of which the following is a specification.

My invention relates to metal railroad-ties, and has for its object to provide a novel 10 tie of this class which may readily be adjusted to clamp and hold the rail by a key or like instrument.

A further object of my invention is the provision of novel and effective means for 15 clamping a rail to the tie.

Still another object of my invention is the construction of novel protecting and supporting means for the upper portion of the tie to which the movable portions of the tie 20 are connected.

With the above and other objects in view my invention consists in the parts, improvements, and combination of parts hereinafter set forth, and pointed out in the claims, it being understood, however, that various changes 25 may be resorted to within the scope of the appended claims in the form, proportion, and arrangement of parts without departing from the principle of my invention or sacrificing any of the advantages thereof.

In this specification and in the accompanying drawings, forming a part thereof, the same reference characters are used throughout to designate the same parts.

In the drawings, Figure 1 is a top plan view of one form of device embodying my invention, the operating parts being shown in dotted lines in locking position. Fig. 2 is a bottom plan view of the device shown in Fig. 35 and showing the locking parts in adjusted position. Fig. 3 is a view similar to Fig. 2, but showing the locking parts in still another adjusted position and showing the channel-bar upon which the tie is supported with 40 parts thereof broken away. Fig. 4 is a central transverse sectional view, and Fig. 5 is a fragmental longitudinal central sectional view of the device shown in Fig. 1.

Referring to the various parts of my device 50 by reference-numerals, 1 designates the top plate of the tie, which may conveniently be made from sheet metal and which has downwardly-projecting side flanges 2. This plate is provided with perforations 3 55 for the rail-holding lugs and with a perforation 4 for the operating-key.

The holding-lugs 5 project upwardly from the plate 1 in pairs, one on each side of the rail, except that between two rails a double lug 5' may be provided. The said lugs 5 60 comprise a somewhat elongated upright portion 6, which is rotatably received in the perforations 3 in the plate 1, and a laterally-projecting portion 7, which latter-named portion has its lower face formed to fit on the top 65 of the bottom flange on the rail.

Immediately beneath the plate 1 the upright portion 6 of the lugs 5 are encircled by strong springs 8. Below the said springs crank-arms 9 are non-rotatably secured to 70 the upright portion 6 of the lugs 5. Each of the said crank-arms is pivotally secured to the bar 10. The uprights 6 are threaded at their lower ends, and a longitudinally-extending bar 11 is bolted thereto beneath the 75 crank-arms 9. The said bar 11 has central perforations immediately beneath the key-opening 4, in which the shaft of the key may be pivoted. The bar 10 is formed with two notches 12 12 in its side adjacent the key-opening 4 in the plate 1. On the side of the bar 10 opposite the notches 12 is a smaller notch 13, which is adapted to receive a pin 14 on the pivoted bar 15. The bar 15 is spring-pressed by a leaf or other spring 16 against 80 the bar 10.

The channel-bar 16', having side flanges 17 and a web portion 18, is adapted to be secured to the downwardly-extending flanges 2 on the plate 1 by means of the additional 90 downwardly and outwardly extending flanges 19 on the sides of the said channel-bar. The vertical flange 19 of the channel-bars 16' and the flanges 2 of the plate 1 are secured together by means of suitable rivets or other 95 fastenings through the openings 20. On the bottom of the channel-bar 16' cross-pieces 22 are secured to prevent the tie from moving endwise upon the road-bed or upon the stringers of a bridge. I have chosen for the 100 purpose of illustration to show two such cross-bars made of angle-iron; but it is evident that the form and number thereof may be varied to suit varying conditions.

The operation of my improved device is as 105 follows: Assuming that the locking devices have been turned in such position that they would clamp the rail if a rail were placed therein, the key is introduced into the opening 4 and is rotated and enters that one of the notches 110 12 nearest the opening 4, having thus contacted with the bar 15 and by this means

having pushed the pin 14 from the notch 13. As the key is rotated further and passes through one complete revolution it moves the bar 10 longitudinally, and thus turns the lugs 5 by means of the crank-arms 9 through a small angle, so that they no longer stand perpendicular to the sides of a rail. The key is then rotated through another revolution in the same direction. During this revolution it enters the second notch 20 and moves the bar 10 still farther, turning the lugs 5, so that the laterally-projecting portion 7 stands approximately parallel to the sides of a rail. The tie is now placed in position beneath the rail and the key is rotated through two turns in a reversed direction, thus firmly clasping lugs 5 upon the flanges of a rail.

It is evident that if a portion of the railway 20 is injured, as by wreck, it will be possible to remove a tie therefrom by simply inserting and turning the key. A tie made in this manner may be inserted in place of another in a very few moments and with little 25 trouble.

Having thus described my invention and pointed out its advantages, what I claim is—

1. In a metallic railway-tie a plate, adjustable means for securing a rail thereto and means beneath the plate for adjusting and securing said means in a plurality of positions with respect to the rail.

2. In a metallic railway-tie a plate, adjustable means for securing a rail thereto, and key-operated means beneath the plate for adjusting the securing means to leave the rail unsecured, to partially secure the rail or to hold it tightly secured.

3. In a metallic railway-tie, a top plate 40 provided with perforations, the tie being adapted to be placed with the perforations on each side of a rail, rotatable fastening means projecting upwardly through the said plate, a means beneath the said plate for rotating the fastening means.

4. A metallic railway-tie comprising a perforated plate, rotatably headed fastening means extending upwardly through said perforations, a key-operatable means beneath 50 the said plate for rotating the said fastening means.

5. A metallic tie comprising a top plate, rotatably headed fastening means projecting upwardly through said plate, key-operated means beneath the said plate for rotating the said fastening means and a channel-bar secured beneath the said plate with its web portion downward.

6. A metallic tie comprising an upper 60 plate, rotatable lugs projecting upwardly

through said plate, key-operated means beneath said plate for locking the lugs, a channel-bar secured beneath the said plate with its web portion downward and means on the bottom of the channel-bar for holding it 65 against longitudinal motion.

7. A metallic tie comprising a top plate, rotatable, headed fastenings projecting upwardly through said plate, key-operated means beneath said plate for rotating the 70 fastening means, and said rotating means comprising a notched bar and cranks pivoted to said bar and secured to said headed fastenings.

8. A metallic tie comprising a top plate, 75 movable fastening means projecting upwardly through said plate, key-operated means beneath the said plate for operating the said fastening means.

9. A metallic tie comprising a top plate, 80 rotatable lugs projecting upwardly through said plate, and adapted to hold the rail thereto, springs on the lugs beneath the said plate, cranks on the lugs beneath the springs and a notched bar to which the ends of the cranks 85 are pivotally connected.

10. A metallic tie comprising a top plate, means projecting from the plate to hold a rail in place thereon, means beneath the said plate for locking the holding means in place, 90 said means being adapted to be released by means of a key inserted through an opening in the plate.

11. A metallic tie comprising a top plate, movable rail-fastening means projecting upwardly through the plate, means beneath the said plate for operating the fastening means, said means comprising a longitudinally-movable bar.

12. A metallic railway-tie comprising a 100 top plate, the said plate being provided with perforations, lugs having sidewise projecting portions at their upper ends projecting through the perforations in said plate, springs on the lower ends of the lugs, cranks 105 beneath the springs, a bar bolted upon the lugs beneath the cranks, a bar to which the ends of the cranks are pivoted, said last-named bar being provided with notches in its side, a spring-operated key-releasable 100 means for locking the last-named bar against longitudinal movement.

In testimony that I claim the foregoing as my own I have hereto affixed my signature in the presence of two witnesses.

ARTHUR BOID MASON.
